ALL-WEATHER AIRPLANE

Lewis C. McCarty, Jr., and Harold G. Felio, New York, N. Y., assignors to The Marine Aircraft Corporation, New York, N. Y., a corporation of New York

Application June 25, 1948, Serial No. 35,226

21 Claims. (Cl. 244—101)

1

This invention relates to airplanes generally, and includes certain features particularly applicable to amphibians and flying boats. The plane of this invention is provided with a pneumatic cushion forming the lower part of the hull or fuselage, and with inflatable cushions on either side of the fuselage or hull (in addition to the usual ailerons or spoilers), these lateral inflatable cushions acting to maintain lateral stability at rest, and in landing and take off operations. The plane of this invention will alight on and take off from land, water, water containing floating ice, and from snow or ice surfaces.

Further objects, features and advantages of the invention are:

1. To provide an improved pneumatic bottom for the fuselage, made of tough, resilient, air tight material which may be inflated to the necessary pressure for absorbing the shocks of landing whether on land, water, snow or ice.

2. To provide a landing cushion as just described with inset wells in which are housed retractable landing wheels. The construction is such that the plane may alight safely on land or water with the landing wheels either up or down, as will be more fully described later.

3. To provide, on each side of the fuselage, an inflatable pneumatic landing cushion. These lateral landing cushions each comprise a flap pivoted near the trailing edge of the wing, and a sheet of air tight, resilient material positioned on the underside of the wing and secured at its trailing edge to the trailing edge of the flap; such assembly being air tight and inflatable for providing landing cushions. These cushions provide hydrodynamic planing surfaces and hydrostatic displacement members for maintaining transverse stability at rest and in landing and take-off operations. In normal flight, these pivoted flaps are streamlined with the wing and the flexible sheet material is flush with the under surface of the wing so that the wing is of normal contour in flight. When pivoted downwardly, they would also have a braking effect with increased lift.

4. The wings of the plane outwardly of said lateral landing cushions are angled upwardly at a dihedral angle to avoid contact with a landing surface.

5. Lateral stability of the plane is achieved by the use of the usual ailerons, where the landing cushions do not extend all the way to the wing tips. However, in a modified form, the lateral cushions may extend to, or nearly to, the wing tips, in which case lateral control is achieved by the use of the usual spoilers, well

2

known in the art, on the upper surfaces of the wings.

6. The main landing cushion, below the bottom of the fuselage is formed of tough, resilient, flexible air tight material secured at its outer edge to the hull or fuselage, from the nose well aft toward the tail. These outer edges are secured to the fuselage or hull at the chine line and contrary to the usual practice, the top of the main landing cushion is not formed of this sheet of flexible material, but is formed by the floor of the fuselage. The floor of the fuselage is preferably provided with two sets of valves, spring loaded, for relieving excess pressure in the main landing cushion in the event of a hard landing, the other set passing air under pressure from the pressurized fuselage into the several compartments of the main landing cushion for keeping them properly inflated.

7. The main landing cushion as well as the lateral landing cushions may be compartmented, that is, may be provided with fore and aft as well as lateral partitions, thereby providing separate compartments for maintaining air pressure in the remaining compartments in the event of a puncture of a particular compartment.

8. The airplane of this invention is preferably provided with a piston engine for driving the usual propeller, and with a jet engine of known construction. The exhaust gases from the piston engine are piped to the jet engine; such exhaust gases not only keep the jet warmed up, but also drive the blower of the jet. Air compressed by this blower is led to the piston engine for supercharging it. In other words, the jet engine, under certain conditions, acts as an exhaust driven supercharger. The jet engine is thus always kept warmed up and so is available to supply additional power instantly, as may be needed for take-off and combat operations.

9. Compressed air from the blower of the jet engine may also be used to pressurize the cabin, and to inflate the main landing cushion, as well as the two lateral cushions on either side of the hull or fuselage.

Further advantages of structure and operation will be described in connection with the accompanying drawings, wherein:

Fig. 1 is a front view of an airplane according to this invention.

Fig. 2 is a side view of the same.

Fig. 3 is a plan view.

Fig. 4 is a cross-section, on an enlarged scale, through the fuselage or hull, taken on the line 4—4 of Fig. 2.

Fig. 5 is a cross-section, on an enlarged scale, taken on the line 5—5 of Fig. 3.

Figs. 6 and 7 are longitudinal and transverse cross sections through the wells for the landing wheels.

Fig. 8 is a cross-section, on an enlarged scale, through the floor of the fuselage or hull.

Fig. 9 is a plan view of a portion of a wing, showing a modification.

Fig. 10 is a diagrammatic view of a jet engine and cooperating parts.

Fig. 11 is a fragmentary front view, enlarged, showing one of the lateral landing cushions in inflated position.

Referring now to these drawings, the airplane comprises the fuselage or hull 2 in which is housed one or more engines for driving the usual propeller 4. The wings 6 extend outwardly from the fuselage in the usual way, the outer portions 8 being angled upwardly at a slight dihedral angle. These wings may be provided with the usual landing wheels 10 foldable into the respective wings.

Secured to the under side of the fuselage or hull 2 and extending from the nose well aft toward the tail is a sheet of tough, resilient, flexible, air tight material 12, treated with rubber or synthetic resin, the outer edges 14 of this sheet being secured air tight to the hull at the chine line 16 thereof. The hull 2 is provided with a floor 18 which cooperates with the flexible sheet 12 to form an air cushion hereinafter referred as the air cushion 12. Contrary to the usual practice, the top of the air cushion 12 is not formed of resilient material, such top being formed by the floor 18 of the fuselage, thereby saving that much weight.

The cushion 12 is provided with one or more longitudinally extending resilient keels or partitions 20 made preferably of thick heavy rubber or the like which will bend on impact and which provides longitudinal compartmentation.

The cushion 12 is also provided with a number of lateral partitions 22 for providing lateral compartmentation, thereby localizing possible loss of air in a punctured compartment to such punctured compartment.

The cushion 12 is formed to have a step 24 and the compartment just to the rear of the step may be inflated to such a degree as to eliminate the step in normal flight, thereby decreasing the drag caused by the presence of the step. Such step, of course, performs its usual function in a take-off from water.

The landing cushion 12 is provided with inset wells 26, the walls forming these wells being flexible and secured air tight to the floor of the fuselage and to the sheet 12. The landing wheels 28 housed in these wells are of the retractable type having the usual shock absorbing cylinders 30.

As shown in dotted lines in Fig. 2, the wheels 28, even in retracted position, extend a small distance below the outer surface of sheet 12 so if the plane should encounter a slight rise in landing, the plane, even with the wheels up, will be given a lift over such obstruction. With this construction, the plane will alight on land, water, snow or ice, with the wheels either up or down, thereby minimizing the possibility of accidents.

The lateral landing cushions, forming an important feature of the present invention will now be described:

These landing cushions, indicated generally at 32, are each formed by a flap 34 pivoted at 36

75

near the trailing edge of each wing and extending outwardly from either side of the fuselage at a substantial distance from the wing tips. A sheet of tough, resilient, flexible material 38 has its leading edge 40 secured to the under surface of wing 6 and its trailing edge to the trailing edge of the flap 34. End walls 44 are provided for completing an air tight landing cushion, which is shown in extended and inflated position in Fig. 5. Sheet 38, instead of terminating at 40, could be reversed at 40 and continued backwardly against the underside of the wing, to complete an air tight bag or balloon. When so inflated, the cushion extends a sufficient distance below the wings for engaging the landing surface, such as water, snow, ice and the like, and serves to prevent the wings from engaging such surface, such clearance being further achieved by the upwardly angled parts 8 of the wings. These landing cushions when inflated and in extended position, as in Fig. 5, ride along on the landing surface and serve to maintain lateral stability; if the plane is landing on water, they displace a certain amount of water, thereby further maintaining lateral balance in landing and take-off operations, and also maintain lateral balance when the plane is at rest.

When deflated, flap 34 would be coincident with the trailing edge of the wing, as in Fig. 5, sheet 38 would be tight against the underside of the wing, so that in normal flight, the normal contour of the wing would be maintained.

When extended, these cushions would also have a braking effect. In normal flight lateral control is maintained by the usual ailerons 50.

In a modification of the invention, as shown in Fig. 9, the lateral landing cushion 42 may extend substantially to the wing tips, in which event lateral control is maintained in normal flight by the use of spoilers 45 on the upper surface of the wings, as well known in the art.

Air under pressure is supplied to the compartments of the main landing cushion 12 and to the lateral cushion 32, in any desired manner. Such air may be supplied from any suitable compressor, by valved pipes connected to the respective compartments. A separate air supply is provided for each compartment for maintaining air pressure therein, even if a particular compartment is punctured.

In one aspect of the invention, the main body of the hull, above the floor 18 may be pressurized, as is well understood in the art, and the floor may be provided with spring loaded valves 52 opening upwardly into the fuselage and with a second set of spring loaded valves 54 opening downwardly into the main air cushion 12. A series of valves of this type may be used, one set for each compartment in the main air cushion 12. In the event of a hard landing, the upwardly opening valves 52 would open, relieving excess pressure and preventing rupturing of the sheet 12. Sheet 12 would also bulge upwardly, as in dotted lines in Fig. 4. Where the cabin is pressurized, the air pressure is maintained therein so that valve 54 would open and allow such air under pressure to enter into the various compartments in the main cushion 12.

In one aspect of the invention, the amphibian may be provided with a jet engine 60 of known construction, illustrated diagrammatically, mounted in the tail of the fuselage, the exhaust outlet 62 from said engine being at the extreme rear end of the fuselage. Such a jet engine normally comprises one or more blowers or fans.

The blower compartment 64 of the jet engine is provided with one or more air take-off pipes 66 provided with valves 68 for providing air under pressure which may be used for pressurizing the cabins and for inflating the main landing cushion 12 and the lateral landing cushions 32. In normal flight, the jet engine is operated at low power by exhaust gases from the piston engine, thru pipe 70, to provide sufficient air under pressure for inflation purposes as above mentioned and for supercharging the main engine thru pipe 71. In other words, the jet engine operates as an exhaust operated supercharger for the piston engine. The jet engine is thereby kept warmed up for supplying additional power when needed, especially for take-off and combat operations.

Air taken in by the suction slot 14 may be supplied to the jet engine where another type of slot is used, in which air under pressure is passed through a wing slot to the top, rear surface of the plane; the blower of the jet engine may be used to supply air to the pressure slot, especially where the lateral inflatable landing cushions would tend to blanket the normal use of such pressure slots, where air under pressure passes upwardly through such slot.

Instead of or in addition to a jet engine in the tail of the plane, a jet engine may be mounted in the trailing edge of the wing, directly behind each of the usual piston engines. The housings for these jet engines may be in effect a rearward continuation of the nacelles of the piston engines with which the respective jet engines are associated. These jet engines also act as exhaust operated superchargers for the respective piston engines, and they may also be used to supply air under pressure for the main and lateral inflatable cushions.

Many features of the present invention are applicable to aircraft in general, whether land planes, amphibians or flying boats; and accordingly the terms "fuselage," "hull," "nacelle" and the like are used in an illustrative and descriptive sense, and not in a restrictive sense.

While the invention has been described in some detail, it should be understood that the invention is not to be restricted to the details illustrated, but may be carried out in other ways.

We claim as our invention:

1. An airplane, comprising a fuselage provided with a floor, a flexible, tough, air tight fabric having its outer edges secured to the fuselage, said fabric being positioned below the floor and extending from the nose of the fuselage aft well toward the tail, said fabric cooperating with said floor to form an air tight chamber, the top of which chamber is formed by said floor, a pair of pivoted flaps carried by the wings of the airplane, one on each side of the fuselage, and tough, air tight flexible material positioned on the underside of the wing, ahead of each flap and secured to the trailing edge of each flap, for forming inflatable resilient air tight cushions for maintaining lateral balance in landing and take-off operations and at rest.

2. A flying boat, comprising a hull provided with a floor, a flexible, tough, air tight fabric having its outer edges secured to the hull, said fabric being positioned below the floor and extending from the nose of the fuselage aft well toward the tail, said fabric cooperating with said floor to form an air tight chamber, the top of which chamber is formed by said floor, a pair of pivoted flaps carried by the wings of the plane, one on each side of the hull and inset from the

trailing edge thereof, air tight flexible material positioned on the underside of each wing, ahead of each flap, and attached to the trailing edge of said flap, and cooperation with its respective flap to form inflatable air tight cushions providing hydrodynamic planing surfaces and hydrostatic displacement members for maintaining transverse stability in landing and take-off operations and at rest.

3. An airplane, comprising a fuselage provided with a floor, a flexible, tough, air tight fabric having its outer edges secured to the fuselage, said fabric being positioned below the floor and extending from the nose of the fuselage aft well toward the tail, said fabric cooperating with said floor to form an air tight chamber, the top of which chamber is formed by said floor, a pair of pivoted flaps carried by the wings of the airplane, one on each side of the fuselage, and tough, air tight fabric positioned ahead of each flap and attached to the trailing edge of each flap, for forming inflatable resilient air tight cushions for use in landing and take-off operations, the wings of said airplane, outwardly of said pivoted flaps, being angled upwardly for clearing the landing surface.

4. A flying boat, comprising a hull, provided with a floor, a flexible, tough, air tight fabric having its outer edges secured to the hull, said fabric being positioned below the floor and extending from the nose of the hull aft well toward the tail, said fabric cooperating with said floor to form an air tight chamber, the top of which chamber is formed by said floor, a pair of pivoted flaps carried by the wings of the plane, one on each side of the hull and inset from the trailing edge thereof, a sheet of tough, air tight, flexible material positioned on the underside of each wing ahead of each flap and attached to the trailing edge of said flap, and cooperating with its respective flap to form inflatable air tight cushions providing hydrodynamic planing surface and hydrostatic displacement members for maintaining transverse stability at rest and in landing and take-off operations, the wings of said flying boat, outwardly of said pivoted flaps, being angled upwardly for clearing the landing surface.

5. An airplane, comprising a fuselage provided with a floor, a flexible, tough, air tight fabric having its outer edges secured to the fuselage, said fabric being positioned below the floor and extending from the nose of the fuselage aft well toward the tail, said fabric cooperating with said floor to form an air tight chamber, the top of which chamber is formed by said floor, a pair of pivoted flaps carried by the wings of the airplane, one on each side of the fuselage, tough, air tight fabric positioned on the underside of each wing, ahead of each flap, and secured to the trailing edge of each flap, for forming inflatable resilient air tight cushions for maintaining lateral stability at rest and in landing and take-off operations, and ailerons carried by the wings of the plane, outwardly of said pivoted flaps.

6. An airplane, comprising a fuselage provided with a floor, a flexible, tough, air tight fabric having its outer edges secured to the fuselage, said fabric being positioned below the floor and extending from the nose of the fuselage aft well toward the tail, said fabric cooperating with said floor to form an air tight chamber, the top of which chamber is formed by said floor, a pair of pivoted flaps carried by the wings of the airplane, one on each side of the fuselage, tough, air tight

fabric secured to the plane ahead of each flap and to the trailing edge of each flap, for forming inflatable resilient air tight cushions for use at rest and in landing and take-off operations, and spoilers for lateral balance carried by the upper surfaces of the airplane.

7. An airplane, comprising a fuselage provided with a floor, flexible, tough, air tight fabric having its outer edges secured to the fuselage, said fabric being positioned below the floor, said fabric cooperating with said floor to form an air tight chamber, the top of which chamber is formed by said floor, a pair of pivoted flaps carried by the wings of the airplane, near the trailing edges thereof and extending for substantially the full length of the wings, air tight flexible material, secured to the underside of each wing, ahead of its flap, and having its rear edge secured to the trailing edge of its respective flap and cooperating therewith to form flexible, inflatable, resilient cushions providing hydrodynamic planing surfaces and hydrostatic displacement members, and spoilers carried by the upper surfaces of the wings.

8. An airplane comprising a fuselage, a pneumatic inflatable landing cushion on the underside of the fuselage, pivoted flaps carried by the wings of the plane, near the trailing edges thereof, and flexible, air tight sheet material cooperating with the underside of the wings and positioned below said pivoted flaps, for forming flexible, air tight, inflatable cushions just ahead of the flaps, for providing when inflated hydrodynamic planing surfaces and hydrostatic displacement members adapted to contact landing and take-off surfaces for maintaining transverse stability in landing and take-off operations.

9. A flying boat, comprising a hull, a pneumatic inflatable landing cushion on the underside of the hull, pivoted flaps carried by the wings of the flying boat, near the trailing edges thereof, and flexible, air tight sheet material cooperating with the underside of the wings and positioned below said pivoted flaps, for forming flexible, air tight, inflatable cushions just ahead of the flaps, for providing when inflated hydrodynamic planing surfaces and hydrostatic displacement members adapted to contact landing and take-off surfaces for maintaining transverse stability at rest and in landing and take-off operations, said sheet of flexible material, when the cushions are deflated, being flush against the underside of the wing, while its cooperating flap is coincident with the trailing edge of its wing.

10. An airplane, comprising a fuselage, a pneumatic inflatable landing cushion on the underside of the fuselage, said cushion being provided with inset wells, landing wheels housed in said wells, pivoted flaps carried by the wings of the plane, near the trailing edges thereof, and flexible, air tight sheet material cooperating with the underside of the wings positioned below said pivoted flaps, for forming flexible, air tight, inflatable cushions just ahead of the flaps, for providing hydrodynamic planing surfaces and hydrostatic displacement members adapted to contact landing and take-off surfaces for maintaining transverse stability in landing and take-off operations.

11. A flying boat, comprising a hull, a pneumatic inflatable landing cushion on the underside of the hull, ailerons carried by the wings at the ends thereof, pivoted flaps pivoted near the trailing edges of the wings, and positioned between the ailerons and the fuselage, and flexible, air

tight sheet material cooperating with the underside of the wings and positioned below said pivoted flaps, for forming flexible, air tight, inflatable cushions just ahead of the flaps, for providing hydrodynamic planing surfaces and hydrostatic displacement members adapted to contact landing and take-off surfaces for maintaining transverse stability in landing and take-off operations.

12. An airplane, comprising a fuselage, a pneumatic inflatable landing cushion on the underside of the fuselage, spoilers carried by the top surface of the wings for lateral balance, flaps pivoted near the trailing edges of the wings, and flexible, air tight sheet material cooperating with the underside of the wings and positioned below said pivoted flaps, for forming flexible, air tight, inflatable cushions just ahead of the flaps, for providing hydrodynamic planing surfaces and hydrostatic displacement members adapted to contact landing and take-off surfaces for maintaining transverse stability in landing and take-off operations.

13. A flying boat, comprising a hull, a pneumatic air tight landing cushion on the underside of the hull, the outer parts of the wings being angled upwardly at a dihedral angle, flaps pivoted to the wings, between said dihedral angle and the hull, near the trailing edges of the wings; flexible, air tight sheet material cooperating with the underside of the wings and with respective flaps, for forming flexible, inflatable cushions just ahead of the flaps, said sheet material, when the cushions are deflated being flush against the underside of the wings, while its cooperating flap is coincident with the trailing edge of the wing, said cushions providing, when inflated, hydrodynamic planing surfaces and hydrostatic displacement members for maintaining transverse stability in landing and take-off operations.

14. A flying boat, comprising a hull, a pneumatic air tight landing cushion on the underside of the hull, said cushion being provided with inset wells, landing wheels housed in said inset wells, the outer parts of the wings being angled upwardly at a dihedral angle, and provided with ailerons, flaps pivoted to the wings, between said dihedral angle and the hull, near the trailing edges of the wings; flexible, air tight sheet material cooperating with the underside of the wings and with respective flaps, for forming flexible, inflatable cushions just ahead of the flaps, said sheet material, when the cushions are deflated being flush against the underside of the wings, while its cooperating flap is coincident with the trailing edge of the wing, said cushions providing, when inflated, hydrodynamic planing surfaces and hydrostatic displacement members for maintaining transverse stability in landing and take-off operations.

15. An airplane, comprising a fuselage, pivoted flaps carried by the wings of the plane, pivoted near the trailing edges thereof, sheet material positioned ahead of said pivoted flaps, and secured to the trailing edges of the flaps, for thereby forming inflatable, air tight landing cushions, providing when inflated, hydrodynamic planing surfaces and hydrostatic displacement members for maintaining transverse stability at rest and in landing and take-off operations.

16. A flying boat, comprising a hull, pivoted flaps carried by the wings, pivoted near the trailing edges thereof, sheet material positioned ahead of and below said pivoted flaps, and secured to the flaps, for thereby forming inflatable, air tight landing cushions, providing when inflated, hy-

ydrodynamic planing surfaces and hydrostatic displacement members adapted to contact landing and take-off surfaces for maintaining transverse stability in landing and take-off operations, said flaps, when folded, coinciding with the trailing edges of the wings, with said sheet material flush against the underside of the wings.

17. An airplane, comprising a fuselage, pivoted flaps carried by the wings of the plane, pivoted near the trailing edges thereof, sheet material secured to the underside of the wings, ahead of said pivoted flaps, and secured at its trailing edge to the trailing edges of the flaps, for thereby forming inflatable, air tight landing cushions, providing when inflated, hydrodynamic planing surfaces and hydrostatic displacement members for maintaining transverse stability at rest and in landing and take-off operations, and flaps, when folded, coinciding with the trailing edges of the wings, with said sheet material flush against the underside of the wings, the wings of the plane, outwardly of said pivoted flaps, being angled upwardly for clearing the landing surface.

18. An amphibian airplane, comprising a fuselage, pivoted flaps carried by the wings of the plane, pivoted near the trailing edges thereof, sheet material secured to the underside of the wings, ahead of said pivoted flaps, and secured at its trailing edge to the trailing edges of the flaps, for thereby forming inflatable, air tight landing cushions, providing when inflated, hydrodynamic planing surfaces and hydrostatic displacement members for maintaining transverse stability in landing and take-off operations, said flaps, when folded, coinciding with the trailing edges of the wings, with said sheet material flush against the underside of the wings, and spoilers carried by the upper wings of the plane, for lateral control.

19. An airplane, comprising a pressurized fuselage provided with a floor, a flexible, tough, air tight fabric secured to the fuselage, said fabric being positioned below the floor, said fabric cooperating with said floor to form an air tight chamber, the top of which chamber is formed by said floor, such chamber providing a pneumatic cushion for alighting and take-off on land, water, snow or ice, and valve means positioned in said floor for passing air from the pressurized fuselage into said air chamber for inflating it.

20. An airplane, comprising a pressurized fuselage provided with a floor, a flexible, tough, air tight fabric secured to the fuselage, and positioned below the floor thereof, said fabric cooperating with said floor to form an air tight chamber, the top of which chamber is formed by said floor, such

chamber providing a pneumatic cushion for alighting and take-off on land, water, snow or ice, and differential valve means positioned in said floor for passing air in either direction between the pressurized fuselage and said air tight chamber, when the air pressure in one exceeds the air pressure in the other by a predetermined amount.

21. An airplane, comprising a fuselage, pivoted flaps, carried by the wings, and pivoted near the trailing edges thereof, sheet material, secured to the underside of the wings, ahead of said flaps, and also secured to the flaps, for thereby forming inflatable, air-tight cushions, providing when inflated, hydrodynamic planing surfaces and hydrostatic displacement members wherein said sheet material contacts the landing and take-off surfaces, said displacement members serving to maintain transverse stability in landing and take-off operations.
